CLAIM

Applicant claims the ornamental design for a wire rope bundling clip, as shown and described.

DESCRIPTION

FIG. 1 is a perspective view of the wire rope bundling clip. FIG. 2 is a front view of the wire rope bundling clip shown in FIG. 1.

FIG. 3 is a rear view of the wire rope bundling clip shown in FIG. 1.

FIG. 4 is a left side view of the wire rope bundling clip shown in FIG. 1.

FIG. 5 is a right side view of the wire rope bundling clip shown in FIG. 1.

FIG. 6 is a top view of the wire rope bundling clip shown in FIG. 1; and,

FIG. 7 is a bottom view of the wire rope bundling clip shown in FIG. 1.

The broken lines in the figures depict portions of the clip that form no part of the claimed design.
